UNITED STATES PATENT OFFICE.

FRANCIS A. NOLAN, OF ST. PAUL, MINNESOTA.

PHONOGRAPH-STOP.

1,319,171.

Specification of Letters Patent.

Patented Oct. 21, 1919.

Application filed May 21, 1917. Serial No. 169,844.

To all whom it may concern:

Be it known that I, FRANCIS A. NOLAN, a citizen of the United States, residing at St. Paul, in the county of Ramsey and State 5 of Minnesota, have invented a new and useful Improvement in Phonograph-Stops, of which the following is a specification.

This invention relates to improvements in stops for sound reproducing machines, 10 which are adapted to automatically cause the arrest of rotation of a record structure when the playing of a record is completed, so as to avoid scratching the record by a needle or stylus. More particularly this invention relates to that class of stops which can be easily attached to or detached from the sound reproducing machine and which can be easily set for arresting the rotation of the record structure at the end of the 15 record, irrespective of the length or kind of sound groove in the record. In other words my invention is adapted to arrest the rotation of the record structure whether the stylus or sound reproducing needle or point 20 plays inwardly or outwardly on the record, that is when the stylus or point travels inwardly toward the center of the record or outwardly toward the periphery. My invention also contemplates certain novel features 25 pertaining to the brake mechanism employed. With these and other objects in view, my invention comprises the features of construction and combination of parts, which will hereafter be more particularly 30 described and claimed.

In the accompanying drawing forming part of this specification, Figure 1 is a plan of a sound reproducing machine of the conventional Victor type to which my invention 40 is shown applied, part of the structure of said machine being broken away and in section; Fig. 2 is a section of a detail taken on the line X—X of Fig. 1; Fig. 3 is a plan of a portion of the structure illustrated in Fig. 45 2, part of said structure being broken away and in section; Fig. 4 is a perspective of the brake base plate; Fig. 5 is a perspective of the stop piece which is used on the brake; Fig. 6 is a perspective of my improved trip 50 for the brake; Fig. 7 is a side elevation of a detail of a sound reproducing machine showing an alternative construction of my invention, part of the structure illustrated being broken away and in section; Fig. 8 is a perspective of the trip member employed in the

construction illustrated in Fig. 7; Fig. 9 is a plan of another alternative construction of trip mechanism which may be employed with my invention, said trip mechanism being mounted on the tone arm, a cross section 60 of which is illustrated; Fig. 10 is a side elevation of the construction of my improved trip mechanism illustrated in Fig. 9, and Fig. 11 is a side elevation of a detail of a tone arm upon which the improved trip 65 mechanism illustrated in Fig. 9 is adapted to be mounted.

Referring to Figs. 1 to 6 of the drawing, A indicates a sound reproducing machine of the Victor or other disk type having the 70 usual turn table 2 and tone arm or sound tube 3, which is swiveled to turn in the usual manner as the sound box with its needle point or stylus tracks in the sound groove of the record on the turn table in the usual 75 manner, either toward the center thereof or outwardly toward its periphery. The turn table 2 has the usual downwardly extending flange 4 on its periphery and arranged to engage the inner surface of this flange is 80 the brake B forming part of my improved stop mechanism. This brake has its break member formed from a single piece of sheet metal or other suitable material having a tiltable brake shoe arm 5 pivoted midway 85 between its ends upon the pivot 6 passing downwardly through a base plate 7, which is secured through the openings 8 by nails or screws 9 upon the top 10 of the body 11 of the sound reproducing machine. Extending 90 laterally from the tiltable member 5 is an operating lever 12 by which the brake shoe member 5 is tilted one way or the other about its pivot. The extremities of member 5 have brake shoe or buffer elements 13 95 and 14, extending outwardly and inwardly therefrom, which are arranged so that when the operating lever 12 is shifted in one direction, braking action is applied against the inner surface of flange 4 by brake shoe element 13 and when said operating lever is reversed, the brake shoe element 14 is impressed against the inner surface of said flange. 100

In median position both brake shoe buffer 105 elements are out of contact with flange 4 as illustrated in Fig. 3. A helical expansion spring 15 has one of its ends secured to an arm 16 extending upwardly from the inner end of the plate 7 and its other end secured 110

to a pin 17 on the outer portion of the operating lever 12, said arm 16 and pin 17 being arranged on a line intersecting the pivot 6 and at right angles to a longitudinal median line passing through member 5. Thus when the operating lever 12 is tilted in either direction, said spring will immediately cause one of the brake shoe elements to be impressed against the inner surface of the rim 4, and stop the turn table from revolving when the operating lever 12 is tilted in either direction. The outer extremity of the operating lever 12 is formed with an upwardly extending shoulder piece 18, and the body 15 of said operating lever is enlarged and formed with an opening 19 and an inwardly projecting stop shoulder 20.

Mounted upon the plate 7 and extending upwardly through opening 19 is a stop piece 21 having two stop lugs 22 and 23, which are adapted according to the position assumed by the stop piece rotatively to prevent swinging movement by the lever 12, either in one or the other direction, and thus limiting the use of the brake element to one of the brake shoes at a time against the flange 4. The stop piece 21 is rotatably mounted upon the shaft 24 projecting upwardly from the plate 7, a cavity 25 being formed in said stop piece through which said shaft projects. The coil spring 26 placed around said shaft in said cavity presses downwardly against the lower end 27 of the stop piece and upwardly against a bur 28, which is rotatably mounted in said cavity and threaded upon the shaft 24. Formed upon the lower end of the stop piece is a key 30, which is adapted to fit into one or the other of the openings 31 and 32 in the plate 7, thus locking the stop piece in either one or the other of the positions thus assumed. The spring 26 holds the stop piece with the key 30 engaged with either one of the openings 31 or 32, but permits the stop piece to be lifted by hand to change its position. When the key 30 is locked in engagement with the plate in one of the openings 31 or 32, one of its shoulders 22 or 23 will prevent movement of the operating lever 12 in one direction, but the space between said shoulder pieces allows the operating lever to swing freely in the opposite direction with its brake shoe on one side pressing against the flange 4. When the stop piece is changed with its key 30 inserted in the other of said openings in the plate 7, the other of said stops 22 or 23 will prevent the movement of the operating lever 12 past dead center in the other direction, but allow free movement of the brake member 5, so that the other of said brake shoe buffers will apply its braking action against the flange 4. The object of providing this mechanism as described is so that a trip member such as C will release and cause the setting of the brake when the sound box is playing out-

wardly or inwardly upon the record carried by the turn table according to the direction of the sound groove in the record.

The trip device C comprises a split collar 35 tightly clamped by the bolt or screw 36 passing through its ends on the vertical portion of the tone arm 3, which is swiveled in the usual manner upon the top 10 of the body 11, said tone arm being adapted to carry the sound box in the usual manner. The collar 35 is formed with an outwardly projecting support 38 upon which is pivotally mounted by the bolt 39 the trip member 40. This trip member has an upwardly projecting handle 42 on its outer free end and is formed with a spring member 43 below the head of the bolt 39, which retards but does not absolutely prevent the movement of the trip arm 40 on its pivot in a horizontal direction. The upturned shoulder piece 18 on the operating lever 12 of the brake and the outer free end of the trip member 40 are so arranged that as the tone arm 3 turns while the sound reproducing point carried by the sound box is moved forwardly in the sound groove of the record being played the edge of the trip member 40 will impinge against the shoulder piece 18 and force the operating lever 12 past dead center. The spring 15 will thereupon automatically set the brake and stop the turn table from revolving.

To adjust the trip member, so that it will apply the brake at the proper instant at the end of playing a record, said trip member is turned in its pivot support, so that it will at the desired time release the brake. To determine this proper instant all that is necessary is to place the needle or point of the sound box at the end of the sound groove in the record to be played while the brake is set, then to move the trip member 40, so that it will abut against the shoulder 18. The point of the sound box should next be adjusted to the beginning of the sound groove and the brake moved by hand into releasing or neutral position as illustrated in Fig. 3. While the record is being played, the sound box traveling toward the end of the sound groove will turn the vertical portion of the tone arm 3, causing the trip member 40 to approach the shoulder 18 until the end of the record groove is reached, whereupon the trip member will release and cause the brake to be set automatically. The operation of the device is very simple, and the adjustment of the parts to operate with different lengths of records can be easily attained by an unskilled operator.

When it is desired to operate the machine, so that the brake will be set automatically in the manner stated when the sound box travels outwardly instead of inwardly upon the record, the sleeve 35 is shifted in position around the tone arm and the bolt 36 tight-

ened when the proper position is reached, so that the turning of the trip member 40 will effect the release of the brake when a long or a short record is played. The stop piece 5 21 is then changed in position with its key 30 inserted in the other of the openings 31 or 32. The adjustment for playing a record is then accomplished in the same manner described above, excepting that the trip member 10 40 will strike against the opposite side of shoulders 18 on releasing arm 12, thus causing the other of the brake shoe buffers to impinge against the flange 4 and stop the turn table revolving when the brake is set. 15 In the construction illustrated in Figs. 7 and 8, the trip member 45 is rigid with the clasp 46, said clasp being formed by a pair of spring arms which are adapted to slip over the collar 47 into the circular groove 20 48. The outer free end of the trip member 45 has a handle piece 49. The collar 47 is fastened upon the tone arm 3 by the screw 50 at proper elevation. The adjustment of member 45, so as to release the brake at the 25 proper instant is accomplished by turning the clasp in its groove 48. When it is desired to change the position of the trip member 45, so that it will operate against the opposite side of the shoulder 18 or to re- 30 move the trip member entirely from the machine, it can be lifted out of the groove 48 without the use of any tools and without loosening the screw 50. When desired the tone arm can be formed with a circular groove 51 in place of the collar 47 to receive the clasp 46.

In Figs. 9 and 10 a rigid supporting arm 54 is secured on the tone arm by screws 52 and a disk 55 eccentrically journaled by the 40 pin or bolt 56 passing through a supporting member 57. The supporting member is also rigidly mounted by the pin or bolt 58 on the inner end of the support 54 and the body of the arm 57 is formed with a downwardly pressing spring pawl 59 positively but releasably engaging with a circular series of ratchet teeth 60, so that when the disk 55 is turned, it is held firmly in adjusted position by said pawl, but not sufficiently to prevent the disk from being turned into adjusted position by hand. In use the disk is turned upon the support 54 to accomplish the function of regulating the trip member to release the brake at the 45 proper instant. In operation the periphery of the disk strikes the stop shoulder 18 to release the brake. The brake mechanism above may be used with or without my improved trip described above and operated by 50 hand when desired. It may also be used with the shoe elements on the outside of the turn table and the double shoe buffers shown

made to impinge or press against the outer surface instead of the inner surface of the flange. The brake may also when desired 65 be constructed with only one shoe element instead of two in which event the movable stop element 21 is unnecessary.

In accordance with the patent statutes, I have described the principles of operation of 70 my invention, together with the apparatus which I now consider to represent the best embodiment thereof, but I desire to have it understood that the construction shown is only illustrative and that the invention can 75 be carried out by other means and applied to uses other than those above set forth within the scope of the following claims.

Having described my invention what I 80 claim as new and desire to protect by Letters Patent is:—

1. The combination in a sound reproducing machine of a turn table, a sound box traveling element coöperating with said turn table, a brake having means whereby it may 85 be released from two directions to stop said turn table, and means carried by said sound box traveling element for releasing said brake in either direction of travel of said traveling element. 90

2. The combination in a sound box reproducing machine of a turn table, a sound box traveling element coöperating with said turn table, a brake having means whereby it may be released in either of two directions to 95 stop said turn table, and adjustable means carried by said traveling element for releasing said brake in either direction of travel of the sound box traveling element.

3. A brake release, comprising, a support 100 having an integral radiating arm adapted to be secured to a traveling swiveled element of a phonograph so that its free end will swing back and forth concentrically therewith and a releasing arm pivotally secured 105 to said radiating arm and movable to cause its outer free end to strike a brake release at a predetermined instant.

4. A brake release, comprising, a support 110 adapted to be secured to the upstanding portion of the tone arm of a sound reproducing machine, said support being formed with a downwardly and outwardly projecting portion and a striker member pivotally supported upon the lower portion of said projection at a point close to the base of said tone arm and adapted to be selectively positioned about an axis on said lower projection to swing horizontally and actuate a 115 brake of a sound reproducing machine. 120

In testimony whereof, I have signed my name to this specification.

FRANCIS A. NOLAN.
